UNITED STATES PATENT OFFICE

LEE B. LANDON, OF ELWOOD, INDIANA, ASSIGNOR TO AMERICAN SHEET AND TIN PLATE COMPANY, A CORPORATION OF NEW JERSEY

COUNTING MECHANISM

Application filed May 15, 1928. Serial No. 277,887.

This invention relates to counting mechanism for counting sheets and plates as they are piled one on top of the other, and has for one of its objects the provision of a counting mechanism particularly adapted for counting tin plate as it is inspected and piled one on top of the other.

Another object is to provide a counting mechanism which is composed of a few single parts, is of relatively light weight, and readily movable from place to place.

In the drawings

Figure 1 is a front elevation of a counting mechanism constructed in accordance with this invention.

Figure 2 is a partial rear elevation thereof.

Figure 3 is a partial sectional side elevation showing the carriage supported on the plates being counted.

Figure 4 is a sectional side elevation taken at right angles to Figure 3.

Figure 5 is a fragmentary detail elevation illustrating the bell ringing mechanism.

Referring more particularly to the drawings, the letter A designates the top of a table or base on which the sheets or plates are piled during the inspection operation. The operator inspects the sheets or plates and then piles them in a second pile or discards them as the case may be. Suitable blocks or supports 2 are preferably positioned on the table and the sheets are preferably piled on these supports to facilitate handling.

The counter of this invention, which is designated generally by the letter B, is composed of a base 3 on which a pair of uprights or standards 4 are secured. The standards 4 are connected at their upper ends by a cross-bar 5, and are slotted longitudinally, as at 6, to provide guideways in which the wheels 7 of a wheeled carriage 8 are adapted to travel.

The carriage 8 is composed of a main body plate 9 on which the wheels 7 are mounted. A pair of supporting arms 10 are secured to the body plate 9 and are adapted to project out over the pile of inspected sheets. The arms 10 are each provided with a roller 12 adapted to engage the uppermost sheet of the inspected pile of sheets.

A bracket 13 is secured to and projects rearwardly from the rear face of the body plate 9 and has a toothed index wheel 14 journaled thereon. The wheel 14 is provided with a number of teeth equal to the number of sheets desired to be counted for each unit or box.

The wheel 14 is adapted to rotate the distance equal to one tooth by each sheet placed on the pile of inspected sheets. A bracket 15 is secured to and projects rearwardly from the rear face of the body plate 9 and a crank-shaped locking dog member 16 is pivotally mounted on said bracket. One arm of the dog member 16 terminates in a head portion 17, and the other arm is adapted to be engaged by a rocking release lever 18. A spring 19 normally tends to urge or force the head 17 of the dog member 16 into locking engagement with the teeth of the wheel 14.

The lever 18 projects through a slot in the body plate 9, at one side of the wheel 14, and is pivotally secured intermediate its ends to a lug 20 secured to and projecting from the forward face of the plate 9.

A second rocking lever 21 projects through a slot in the body plate 9 at the opposite side of the wheel 14 from the lever 18 and is pivotally secured intermediate its ends to a lug 22, secured to and projecting from the forward face of the plate 9. The rear end of the lever 21 has an operating dog 23 pivotally secured thereto which is constantly maintained in yieldable contact with the teeth of the wheel 14.

The levers 18 and 21 are provided with cam-shaped slots 25 adjacent the forward ends in which the upper ends of operating levers 26 are adapted to ride to rock the levers 18 and 21 about their pivotal mountings. The levers 26 have their lower ends rigidly connected to a rock shaft 27 journaled in bearings in the arms 10. A pair of trip levers 28 are connected to and depend from the shaft 27 and are adapted to be engaged by the sheets or plates to rock the shaft 27 and levers 26, so as to move the upper ends of the levers 26 in the slots 25 and thereby rock the levers 18 and 21 so as to move the rear ends upwardly. Springs 29 are connected to ten-

sioning levers 30 mounted on the body plate 9 and to arms 26^a, on the shaft 27, and are adapted to be tensioned as the levers 26 are rocked forwardly by the shaft 27 and to return the levers 26, shaft 27 and levers 28 to their normal position.

In operation, as the operator moves an inspected sheet onto the pile, he will move the sheet rearwardly against the levers 28, therefore by forcing said levers rearwardly and rocking the shaft 27 so as to move the levers 26 forwardly. As the levers 26 move forwardly their upper ends will traverse the cam slots 25 in the levers 18 and 21 so as to rock the rear ends of said levers upwardly, thus causing the operating dog 23, on the lever 21, to rotate the wheel 14 and release the locking dog 16 so that its head 17 will engage in the teeth of the wheel 14 and limit its movement to one tooth.

The operating dog 23 is held in engagement with the wheel 14 at all times, while the locking dog 16 is held out of engagement when the actuating levers 28, shaft 27 and levers 26 are in their normal position; therefore, when the levers 28, shaft 27 and levers 26 are caused to move by the sheet being piled, the locking dog 16, which requires a material amount of travel before it engages the wheel 14, will not engage said wheel until after the operating dog 23 has advanced the wheel one tooth or notch.

After the operator has forced the sheet into engagement with the levers 28, to cause the above operation, the sheet or plate will be released and the springs 29 will return the levers 26 and their associated parts to normal position and, at the same time, force the sheet into alignment with the remainder of the pile.

In order to register or advise the operator when a unit consisting of the desired number of sheets has been assembled, a bell 32 is mounted on the plate 9 and a spring operated knocker or hammer 33 is mounted on a bracket 34 and adapted to be tripped by a tripping lug 35 on the wheel 14. When the device is first set in operation the lug 35 will be set immediately beyond the tripping position, then when one complete revolution of the wheel is made, and upon each subsequent revolution, the bell will be rung to indicate the completion of a unit composed of a number of sheets equal to the number of teeth on the wheel.

While I have shown and described one specific embodiment of my invention, it will be understood that I do not wish to be limited thereto since various modifications may be made without departing from the scope thereof as defined in the appended claims.

I claim—

1. A counting mechanism for sheets and plates comprising a base, a pair of spaced standards secured to said base, a carriage adapted to move vertically in said standards,

a toothed index wheel mounted on said carriage for rotation about a horizontal axis, a rocking lever pivotally supported on said carriage for movement about a horizontal axis at right angles to the axis of said wheel, an operating dog pivotally mounted adjacent one end of said rocking lever and adapted to engage and rotate said wheel when said rocking lever is moved in one direction about its axis, means for maintaining said dog in engagement with said wheel, a horizontal rock shaft journaled in said carriage, a depending lever secured to said shaft and adapted to be engaged by the sheets to be counted to rock said shaft, said rocking lever having a cam slot therein adjacent the end remote from said operating dog, and a lever secured to said rock shaft and extending upwardly, the upper end of said last named lever being engaged and adapted to ride in said cam slot to actuate said rocking lever.

2. A counting mechanism for sheets and plates comprising a base, a pair of spaced standards secured to said base, a carriage adapted to move vertically in said standards, a toothed index wheel mounted on said carriage for rotation about a horizontal axis, a rocking lever pivotally supported on said carriage for movement about a horizontal axis at right angles to the axis of said wheel, an operating dog pivotally mounted adjacent one end of said rocking lever and adapted to engage and rotate said wheel when said rocking lever is moved in one direction about its axis, means for maintaining said dog in engagement with said wheel, a horizontal rock shaft journaled in said carriage, a depending lever secured to said shaft and adapted to be engaged by the sheets to be counted to rock said shaft, means adapted to automatically return said depending lever and rock shaft to normal position when the sheet is released whereby said sheet will be moved into a predetermined position by said depending lever, said rocking lever having a cam slot therein adjacent the end remote from said operating dog, and a lever secured to said rock shaft and extending upwardly, the upper end of said last named lever being engaged and adapted to ride in said cam slot to actuate said rocking lever.

In testimony whereof, I have hereunto set my hand.

LEE B. LANDON.
